ILLUMINATING DEVICE FOR HYDROMETERS AND THE LIKE

Gosta Richard Carlson, Raritan, N. J.

Application November 26, 1932
Serial No. 644,527

3 Claims. (Cl. 240—6.4)

This invention relates to an illuminating device for hydrometers and the like, the general object of the invention being to provide a holder for the hydrometer containing a window and an electric bulb for illuminating a part of the hydrometer which is visible through the window so that the hydrometer or other testing instrument can be readily read.

This invention also consists in certain other features of construction and in the combination and arrangement of the several parts to be hereinafter fully described, illustrated in the accompanying drawings and specifically pointed out in the appended claims.

In describing the invention in detail, reference will be had to the accompanying drawings wherein like characters denote like or corresponding parts throughout the several views, and in which:—

Figure 1 is a view of a hydrometer showing the device applied thereto.

Fig. 2 is a vertical sectional view through the body of the device which carries the battery and bulb.

Fig. 3 is a top plan view of the device shown in Fig. 2.

Fig. 4 is a bottom plan view with the battery and cap removed.

Fig. 5 is a view of the cap.

Fig. 6 is a view of the contact member.

Fig. 7 is a view of the disk of insulating material.

Fig. 8 is a sectional view through the window member.

In these drawings, the numeral 1 indicates the body of the device which is formed at its outer edge with a vertically arranged chamber 2 terminating short of the top of the body and having its lower end extending below the lower edge of the body and this end is exteriorly threaded to receive the closing cap 3. This chamber is adapted to receive a battery 4 and a substantially L-shaped contact member 5 which has its long arm fastened to a part of the body 1 by a screw or the like passing through the opening 6 in said long arm and insulated therefrom.

The short arm has an intermediate offset downwardly extending part which is arranged adjacent the top of the chamber and is adapted to engage the upper post of the battery as shown in Fig. 2. A screw 7 passes through the cap and has an enlarged head 8 whereby the screw can be turned to a position where its free end will engage the battery and force the battery against the contact member 5 and thus close the circuit to the bulb 9 the base of which is

threaded in a socket member 10 which passes transversely through the body 1 with its reduced end located in the chamber 2 and engaging the lower end of the long arm of the contact member 5.

That side of the body opposite the side which carries the chamber 2 has a concave recess therein in which the bulb 9 is located, as shown in Fig. 2. The upper and lower projecting portions formed by this recess carry the substantially semi-circular clamps 11 each of which has an inner lining 12 of felt or the like. These clamps are adapted to engage portions of a hydrometer such as shown at A in Fig. 1 and after the clamps are so engaged with the hydrometer a housing B of the shape shown in Figs. 1 and 8 is placed over the hydrometer into engagement with portions of the body 1 and the clamps 11.

This member B is formed with a window 13 and said member is of substantially semi-circular shape with the flanges 14 extending from the side edges thereof for fitting over portions of the body 1, these flanges covering the concave recess in the body so that the rays of light from the bulb are confined and will illuminate that portion of a hydrometer over which the device is placed so that the reading of the hydrometer can readily be made through the window 13, as shown in Fig. 1.

Thus I have provided means for facilitating the reading of the scale on a hydrometer or similar device. A disk 15 insulates the contact member from the top wall of the chamber.

It is thought from the foregoing description that the advantages and novel features of the invention will be readily apparent.

It is to be understood that changes may be made in the construction and in the combination and arrangement of the several parts provided that such changes fall within the scope of the appended claims.

Having thus described my invention, what I claim as new is:—

1. A device for facilitating the reading of a hydrometer or the like comprising a body having a recess therein opening out through one edge of the body with its ends spaced from the upper and lower ends of the body, a lamp in said recess, a pair of split ring clamps connected to said edge of the body, one at the top and the other at the bottom, for engaging the hydrometer and an elongated housing having an elongated opening therein, having its ends fitting over the clamps with the walls of the opening engaging the body, with the ends of the housing being open, said housing covering part of the hydrometer and having a

window therein for exposing a portion of the hydrometer.

2. A device of the class described comprising a body having a recess therein opening out through one edge of the body and through portions of the sides thereof, a lamp in said recess, split ring clamps attached to said edge of the body, one above the recess and the other below the recess, a housing having an opening in one side thereof with its ends fitting over the clamps, flanges extending outwardly from the walls of the opening in the housing for covering the sides of the recess, said housing having its ends open and a window in a part of the housing, said body having a chamber adjacent that edge which is opposite the edge having the recess therein, said chamber opening out through one end of the body, a battery in said chamber, an L-shaped member in the chamber having one limb engaging a contact of the lamp and its other limb adapted to engage a part of the battery, a cap for closing the open end of the chamber and a screw carried by the cap for forcing the battery against the second limb of the L-shaped member.
15. 3. A device of the class described comprising a body having a recess therein opening out through one edge of the body and through portions of the sides thereof, a lamp in said recess, split ring clamps attached to said edge of the body, one

above the recess and the other below the recess, a housing having an opening in one side thereof with its ends fitting over the clamps, flanges extending outwardly from the walls of the opening in the housing for covering the sides of the recess, said housing having its ends open and a window in a part of the housing, said body having a chamber adjacent that edge which is opposite the edge having the recess therein, said chamber opening out through one end of the body, a battery in said chamber, an L-shaped member in the chamber having one limb engaging a contact of the lamp and its other limb adapted to engage a part of the battery, a cap for closing the open end of the chamber and a screw carried by the cap for forcing the battery against the second limb of the L-shaped member.
